United States Patent Office.

HENRY L. BUDD, OF NEW YORK, N. Y.

Letters Patent No. 64,191, dated April 30, 1867.

IMPROVEMENT IN GRATE-BARS.

The Schedule referred to in these Letters Patent and making part of the same.

TO ALL WHOM IT MAY CONCERN:

Be it known that I, HENRY L. BUDD, of the city and State of New York, have invented, made, and applied to use a certain new and useful Improvement in Grate-Bars for Furnaces; and I do hereby declare the following to be a full, clear, and exact description of the said invention, reference being had to the annexed drawing, making part of this specification, wherein—

Figure 1 is a plan of two of said grate-bars.

Figure 2 is a side view of one bar; and

Figure 3 is a section at the line *xx*.

Similar marks of reference denote the same parts.

The action of heat upon furnace-bars is not equal. Sometimes the middle of the bar will be burnt out while the ends are uninjured; at other times the bar will be warped upwards in the centre, rendering the furnace-grate uneven.

The nature of my said invention consists in a series of cross-bar sections supported on and connected with a longitudinal bar, that is supported in the furnace, said cross-bars being interlocked so as to support each other. By this construction one or more of the cross-bars may be removed when burnt out, without the loss of the other uninjured parts of the bar, and the longitudinal sustaining bar being below the fire-bed is not unduly heated or warped.

In the drawing, *a* is the longitudinal bar supported at its ends in suitable notched bearers. *bb* are the sectional cross-bars setting upon and attached to the bar *a*, and interlocking with each other. I have shown the cross-bars *b*, as formed with a mortise, 1, for the bar *a* to pass through, with side-pieces 2 2 sustaining the fire surface 3, so as to form a triangle, and at 4 4 the bars are interlocked. The sections are kept together by keys or pins passing through the ends of the bar *a*, and I introduce at suitable distances apart sections, *b*, formed with lugs 5 5, which, coming against corresponding lugs in the contiguous bars, leave longitudinal openings between the respective grate-bars. The surfaces 3 may be grooved, if desired, and the side-pieces 2 2 should be rounded on their edges and made as thin as consistent with the required strength so as to give free air spaces. The supports 2 of the bars may be omitted every alternate bar, as the interlocking 4 will support the intermediate bar.

What I claim, and desire to secure by Letters Patent, is—

A furnace grate-bar formed of a series of sections, *b*, attached to the longitudinal bar *a*, said sections interlocking and being constructed substantially as specified.

In witness whereof I have hereunto set my signature this twenty-eighth day of February, A. D. 1867.

HENRY L. BUDD.
